Des. 221,286
Patented July 27, 1971

221,286

DRINKING VESSEL

John W. Kern, Jr., 733 Coral Tree Drive, West Covina, Calif. 91790, and Frank R. Morgan, 528 S. Barrance, Covina, Calif. 91722

Filed May 21, 1970, Ser. No. 33,081

Term of patent 7 years

Int. Cl. D7—01

U.S. Cl. D36—8

FIG. 1 is a perspective view of a drinking vessel showing our new design; and

FIG. 2 is a reduced scale elevational view thereof.

We claim:

The ornamental design for a drinking vessel, as shown.
